VEHICLE DOOR BUMPER

Henry H. Slingerland, Jr., 2800 Ramona Court,
Wilmette, Ill. 60091

Filed Nov. 20, 1974, Ser. No. 525,629

Term of patent 14 years

Int. Cl. D12—16

U.S. Cl. D12—167

FIG. 1 is a front elevational view of a vehicle door bumper showing my new design, it being understood that the broken lines are for illustrative purposes only;

FIG. 2 is a front elevational view thereof to an enlarged scale;

FIG. 3 is a rear elevational view thereof to an enlarged scale;

FIG. 4 is a perspective view thereof to an enlarged scale;

FIG. 5 is a top plan view thereof to an enlarged scale;

FIG. 6 is a right end elevational view thereof to an enlarged scale; and

FIG. 7 is a left end elevational view thereof to an enlarged scale.

The undisclosed bottom is a mirror image of the top shown in FIG. 5.

I claim:

The ornamental design for a vehicle door bumper, as shown and described.
